UNITED STATES PATENT OFFICE.

SAMUEL LIPSIUS, OF NEW YORK, N. Y.

PRINTING APPARATUS.

1,149,455.

Specification of Letters Patent. Patented Aug. 10, 1915.

Application filed September 10, 1914. Serial No. 860,989.

To all whom it may concern:

Be it known that I, SAMUEL LIPSIUS, a citizen of the United States, and residing at New York, in the county of New York and State of New York, have invented a new and Improved Printing Apparatus, of which the following specification is a full disclosure.

This invention proposes an improved apparatus for producing raised printing simulating embossing.

Among the objects of the invention may be noted the provision of an inexpensive and reliable apparatus for accomplishing, independently and in conjunction with each other, a number of operations directed to the production of raised printing without the use of dies, said apparatus effecting the automatic application of a suitable amalgamating ingredient to the ink of a freshly printed surface, the automatic removal therefrom of superfluous portions of said ingredient, and the automatic subjection of the thus prepared printing to a suitable range of fusion temperatures, and finally effecting a discharge of the paper at a point where it may be conveniently utilized.

Other objects will be in part obvious from the annexed drawings and in part indicated in connection therewith by the following analysis of this invention.

This invention accordingly consists in the features of construction and combination of parts, and in the unique relations of the members and in the relative arrangement, disposition and coöperation thereof; all as more completely outlined herein.

To enable others skilled in the art so fully to comprehend the underlying features thereof that they may embody the same by the numerous modifications in structure and relation contemplated by this invention, drawings depicting a preferred form of apparatus have been annexed as a part of this disclosure, and in such drawings, like characters of reference denote corresponding parts throughout all the views, of which:

Figure 1 is a longitudinal sectional elevation illustrating a preferred type of apparatus embodying certain features of the present system. Fig. 2 is a plan, partly in section, of portions of the dusting and heating apparatus shown in Fig. 1. Fig. 3 is a longitudinal elevation, partly in section,

of the apparatus of Fig. 1 applied to a cylinder press.

In approaching a consideration of this invention, it should be noted that for many years attempts have been made to produce without the use of expensive plates or dies the clear-cut uniform linear or stippled characters obtained in the various engraving systems. While such attempts have been successful to a certain extent in isolated instances, it may be safely said that the systems evolved have not brought the art of raised printing into general use. The present invention, relating as it does to an improved apparatus for producing raised printing capable of operation in an entirely automatic manner, obviates many of the obstacles to success found in prior-art systems and conduces, by its very simplicity and effectiveness, to the production of imitation engraving at a low cost both for equipment and operation. The term printing, as herein used, is intended to indicate the systems that form characters in ink on paper or other material, in contradistinction to such operations as coating and altering the color of characters by applying a metallic non-absorbent material thereon.

Referring now more particularly to Fig. 1 of the drawings, there is illustrated at 1 a feeding table from which freshly printed sheets of paper are fed manually to the grippers of the revolving cylinder 2 whose surface passes during a fraction of each revolution through a container 3 filled with powder, forming what might be termed a powder bath. The powder herein contemplated is non-metallic, and in the form of microscopic grains or crystals and of a composition adapted at normal temperatures to adhere to the wet ink on the paper, and at an elevated temperature readily fuse to and thereupon amalgamate with the ink; becoming sufficiently translucent in fusion to adopt the color of the ink; as distinguished from a metallic opaque substance designed to conceal permanently the color of the ink. A powder of the composition set forth in the Crump Patents 644,281 and 644,282, or of the type in commercial use, or of any suitable type, may be used. The container wall extends far enough around the cylinder to prevent the escape of powder.

After one or more revolutions of each

sheet of paper around the cylinder through the powder, the sheet is released at a point adjacent the duster-conveyer 4; upon which the sheet then moves toward the right (Fig. 1) through the second stage of the apparatus beneath a suction hood 5 and over a hopper 6. During the passage of the sheet along the duster-conveyer, the sheet is agitated one or more times by suitable means such as the duster-cams 7 positioned between adjacent belts 8 (Fig. 2) of the duster-conveyer 4; in this way avoiding any physical contact between the inked surface and the agitators, and maintaining the sheet in an approximately horizontal plane with the freshly inked side uppermost, in order to retain on the inked portions as much powder as possible. While in many respects it is immaterial just how the sheet is agitated, it has been found preferable to raise first the head end or right-hand end (Fig. 1) of the sheet at a point far enough along the duster-conveyer 4 so that the sheet is entirely under the suction hood 5, thus causing the superfluous powder to travel toward the left relatively to the sheet, without, however, permitting the lighter portions to escape from the hood 5 to the cylinder 2, where they might prove detrimental by interfering with the work of the grippers and gears. As will be clear from the drawings, the heavier portions of superfluous powder drop into the duster-hopper 6 whence they may be removed through the discharge opening 9, while the lighter particles are drawn away through a suction device (not shown) connected with the hood 5; suitable means (not shown) may be provided for settling and reclaiming the powder passing through the suction device.

Opposite the right-hand roller 10 of the duster-conveyer, where the sheets are discharged at the end of the second stage of the operation of the apparatus, is a heater-conveyer 11 composed preferably of a pair of longitudinally disposed chains 12 passing over suitably spaced sprockets 13 and separated by lateral wires 14 spaced a few inches apart throughout the entire length of the endless conveyer, the separation of the wires measured lengthwise of the conveyer being considerably less than the size of the smallest sheets for which the conveyer is designed, so that the sheet is virtually carried upon a skeleton of transverse wires moved at right angles to their length through whatever path the conveyer may have. In the present instance this path may be roughly described as a flat isosceles triangle comprising the upward side 15 and downward side 16 for the forward movement and the approximately horizontal base 17 for the return movement. Within this triangle is provided a heating device such as a series of gas jets 18 of appropriate spacing and

relative intensity, and controlled from without by a manually operated valve 19. Undue loss of heat is prevented by the heater hood 20 extending approximately from end to end of the heater-conveyer and shaped in approximate conformity to the contour of the upward and downward portions 15, 16 of the conveyer path.

Each sheet discharged from the duster-conveyer at 10 is taken up automatically by the heater-conveyer 11 at the left-hand pair of sprockets 13 thereof, and is carried upward through a zone of progressively increasing temperature, owing to the fact that the heated air collects in the apex of the heater-hood 20. In this manner the powder adhering to the inked portions of the sheet is subjected to a thermo-chemical treatment and becomes incorporated into the ink itself, giving body to the ink and causing the combined ink and powder to appear as raised homogenous lines or characters, in successful imitation of the expensive products of the engraver's art. The maximum temperature to which the sheet is subjected is encountered approximately at the apex 21 of the conveyer triangle 15, 16, 17, where the sheet begins its downward travel through progressively decreasing temperatures to the terminal sprockets 22, whence the sheet may be discharged to a suitable receiving device indicated at 23, or if preferable to another conveyer (not shown).

From this it will be seen that, with the apparatus illustrated in Fig. 1, a sheet of paper with the ink not yet dry is fed manually from the table 1 to the cylinder 2, upon which it passes through powder at 3, thus completing the first stage of the system; the sheet then travels over the duster-conveyer 4 where it is agitated by the duster-cams 7 to remove superfluous powder, this forming the second stage; the third stage comprises the passage of the sheet through the heating dome 20, where it is subjected to progressively increasing and then progressively decreasing temperatures to incorporate the powder into the ink, with the result that a raised-printing effect is produced, in remarkable imitation of engraving. The above, as will be noted, involves manual feeding of the sheets to the first stage of the system, but is entirely automatic in other respects.

In order to provide an apparatus which is fully automatic and at the same time economical of space, the apparatus of Fig. 1 is to be directly cooperatively combined with a press in which the preliminary printing is performed; the first or powdering stage of the raised-printing system following immediately after the printing operation in the press itself, and requiring no manual attention for the sheets in transit from the printing stage to the powdering stage. This

aspect of the present invention, is indicated diagrammatically in Fig. 3. Here the sheets to be printed are fed from the table 24 of a Campbell or other press to the printing cylinder 25, around which they are carried during the printing process and then discharged to a feeding conveyer 26 which carries them to the powdering cylinder 2, after which the operations occur as indicated in connection with Fig. 1. In like manner, the apparatus of Fig. 1 may be coöperatively combined with a hand, semi-automatic or full-automatic press of any one of a variety of types in such a way as to receive the sheets directly as they are discharged from the press, eliminating in this way any intermediate handling of the sheets between the printing operation and the operations illustrated in Fig. 1.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

Having thus revealed this invention, I claim as new and desire to secure the following combinations, elements, or equivalents thereof, by Letters Patent of the United States:—

1. An automatic apparatus for producing raised printing combining a conveyer for a freshly-inked and powdered sheet of paper, said conveyer being constructed to carry said sheet gradually upward and then downward, a hood containing said conveyer for applying to said sheet a sufficiently high temperature to fuse the powder by the heat and thereby form raised-printing, and means for internally heating said hood.

2. An automatic apparatus for producing

raised printing combining means for supporting a freshly inked sheet of paper, a powder bath containing an ink-absorbing ingredient, means for passing the sheet through said bath whereby a portion of said ingredient adheres to said sheet, and means for removing the ingredient from the non-inked portions of the sheet.

55

3. An automatic apparatus for producing raised printing combining a powder bath containing a non-metallic ink-absorbing ingredient readily fusible with heat, a cylinder adapted to support a freshly printed sheet of paper and having its lower surface extending below the normal surface of the powder and adapted to carry said sheet through the bath, and means for rotating said cylinder.

65

4. An automatic apparatus for producing raised printing combining a conveyer adapted to carry a freshly inked and powdered sheet in an upward and then downward direction, a hood over said conveyer and shaped in approximate conformity to the path of said sheet, and a source of heat near said path whereby said sheet is subjected to a progressively increasing temperature in its travel along said conveyer, to fuse said powder into said ink to form raised printing.

70

5. An automatic apparatus for producing imitation engraving combining a conveyer for carrying separate sheets through in inverted position with their freshly printed areas facing downwardly; means comprising a powder bath for applying a fusible resinous powder to inverted areas of said sheets; and a fusion oven adapted to melt the powder adhering to the inked lines during the transit of said sheets.

80

In witness whereof, I hereunto subscribe my name, as attested by the two subscribing witnesses.

SAMUEL LIPSIUS.
